Design No. 18,256, dated April 10, 1888.

2027

2027

UNITED STATES PATENT OFFICE.

LOUISE SODERHOLM, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 18,256, dated April 10, 1888.

Application filed February 23, 1888. Serial No. 265,050. Term of patent 3½ years.

To all whom it may concern:

Be it known that I, LOUISE SODERHOLM, of the city, county, and State of New York, have invented and produced a new and original Design for a Pattern of a Miss's Costume; and I do hereby declare that the engraved prints accompanying this specification convey to any one accustomed to using paper patterns a clear understanding of how a garment made up by the pattern will appear.

The design shows a round waist and a walking-skirt. The skirt displays a front drapery falling nearly to the edge at the center and shorter at the sides, and exhibiting draping plaits at the belt and in the side edges; a full back drapery falling even with the front drapery at the sides and almost to the edge of the skirt at the center, and displaying a down-

ward-turning plait in either front edge and a looping at the center. The waist displays full fronts and a full back that exhibits a fullness at the lower edge, and side plaits extending some distance below the neck and shoulders; a standing collar, and coat-sleeves that display long puffs having side plaits extending some distance below the top, and a fullness at the lower edge.

What I claim as my invention, and desire to secure by Letters Patent, is—

The design for a miss's costume, as shown in the engraved prints accompanying this specification.

LOUISE SODERHOLM.
